UNITED STATES PATENT OFFICE.

GEORGE CROUCH, OF NEW YORK, N. Y.

DESIGN FOR A TRUNK-LID LIFTER.

SPECIFICATION forming part of Design No. 16,879, dated August 31, 1886.

Application filed July 19, 1886. Serial No. 208,502. Term of patent 7 years.

To all whom it may concern:

Be it known that I, GEORGE CROUCH, of the city and State of New York, have invented a Design for a Trunk-Lid Lifter, of which the following is a specification.

This design is represented in the accompanying drawings, in which Figure 1 is an elevation. Fig. 2 is a section at the line *x x*, and Fig. 3 is a section at the line *y y*.

The strap portions 2 and 3 are vertical continuations of the curved bar 4, the outline of said curved bar being ellipsoidal, with the upper and back edge of the bar in the same plane as the back surfaces of the strap portions 2 and 3, and the lower front portion of the bar 4 projecting as a compound curve and leaving a hollow below and behind the said bar 4. There are holes at 5 through the vertical strap portions 2 and 3 of the lifter,

and the outlines of the straps adjacent to the holes are rounding, and the surfaces of the strap portions 2 and 3 are shown as ornamented with ribs 6 at the edges.

This design for a trunk-lifter is neat and artistic in its appearance, and the outline is smooth and rounding.

I claim as my invention—

The design for a trunk-lid lifter, the same consisting in the shape and configuration of the compound curved bar 4 and the vertical strap portions 2 and 3 at the ends thereof, substantially as described and represented.

Signed by me this 15th day of July, A. D. 1886.

GEO. CROUCH.
